UNITED STATES PATENT OFFICE.

FREDERICK W. McCLOSKEY, OF EDGEWOOD, PENNSYLVANIA, ASSIGNOR TO WESTINGHOUSE ELECTRIC & MANUFACTURING COMPANY, A CORPORATION OF PENNSYLVANIA.

BRUSH HOLDER.

Application filed June 24, 1924. Serial No. 722,039.

To all whom it may concern:

Be it known that I, FREDERICK W. McCLOSKEY, a subject of the King of Great Britain, and a resident of Edgewood, in the county of Allegheny and State of Pennsylvania, have invented a new and useful Improvement in Brush Holders, of which the following is a specification.

My invention relates to dynamo-electric machines and it has particular relation to a totally inclosed brush holder construction for preventing carbon side wear in machines employing ventilation by means of air drawn from outside the machine frame.

The problem of carbon side wear has become quite a serious difficulty, particularly in the operation of railway motors in cities where there is a large quantity of sand, particularly cities at or near the coast. In some instances, the brushes have actually worn half-way through, on one side, due to sand or grit, before they were removed from the motor, and it was found that the end wear on the brushes was slight. It was at once evident that if some means could be designed to prevent the carbon side wear, the destruction of the commutator and the danger of a flash-over could be avoided and the life of the brushes could be increased many fold. Extensive tests in service have demonstrated conclusively that the protection of brushes against grit eliminates the side wear as a factor in brush life.

According to my present invention, I provide a dynamo-electric machine having a construction wherein the ventilating air is drawn over the current-collecting device as usual, but wherein the brush holders are totally inclosed, so as to protect the brushes and the spring mechanism of each holder from contact with the grit-laden ventilating air. Each brush holder is provided with an opening in its top to provide access to the brush box, and said opening is normally closed by a removable cap member. A separate handle member is provided for the brush holder, whereby the cap may be easily removed and whereby the spring finger bearing on the top of the brush may be raised by attaching the handle member as an extension on the end of the spring finger.

In prior designs of brush holders, wherein the top of the brush box was left open, it was necessary to leave the brush holder

open also at the bottom of the compartment containing the spring mechanism, in order to prevent the accumulation of dust and grit which would clog up the spring. According to my invention, since no dust or grit is admitted, it is possible to totally inclose the bottom of the brush holder casing thereby protecting the spring from arcs in case of flash-overs on the commutator cylinder.

With the foregoing and other objects in view, my invention relates to the combinations and details of construction hereinafter described and claimed and illustrated in the accompanying drawing, wherein

Figure 1 is a longitudinal sectional view showing the general ventilating scheme of a direct-current railway motor embodying my invention,

Fig. 2 is a detailed end elevation, partly in section, showing my improved brush holder, and

Fig. 3 is a perspective view of the detachable handle member thereof.

In the accompanying drawing, my invention is shown as being applied to a direct-current railway motor comprising a stator or field member 1 and a rotor or armature member 2. The stator member is provided with suitable supports carrying brush holders 3 in operative relation to a commutator cylinder 4 mounted on the rotor or armature member 2. A fan member 5 on the rear end of the armature member provides ventilation for the motor as indicated by the arrows. Any suitable ventilating system may be utilized and no further description thereof is necessary.

The brush holder 3 to which my invention more particularly relates comprises a housing member 6 having a compartment 7 for the spring mechanism and a brush box 8 for carrying a brush 9. The front and rear walls 10 and 11 of the brush box are provided with recesses 12 and 13, respectively, for receiving the end of the laterally extending spring arm 14 of the spring mechanism which may be of any suitable or usual construction, preferably comprising a spiral spring member 15.

The brush-holder housing 6 is provided with an opening in the top thereof immediately to the rear of the recess 13 in the rear wall 11 of the brush box 10 and the remain-

der of the housing is totally inclosed. A housing extension 18 is provided adjacent to the recesses 12 in the front wall 10 of the brush box for receiving the end of the spring 5 arm 14.

The front and side walls of the housing extension 18 extend to the same height as the side walls of the brush box 10 to provide a flat surface which may be totally 10 covered by a removably mounted cap member 21. In the form of embodiment of my invention shown in the drawing, the cap member 21 is pivotally mounted on the housing extension 18 and is held in operative 15 position by means of spring clips 22. The top of the cap member carries a suitable perforated lug 23 which may be utilized for the purpose of lifting off the cap member to gain access to the brush box. The 20 brush holder carries the usual supporting brackets 25 and terminal lugs 26 for the flexible lead-in conductors.

The provision of the housing extension 18 surrounding the front end of the spring 25 arm makes it quite difficult to lift the spring arm in order to remove the brush, and I have devised a novel removable handle member or spring-arm extension 27 comprising a straight lever portion 28 carrying a bent 30 sheet-metal clip 29 providing a socket 30 on one side of the lever member at a point removed from the end 31 of the lever member, said socket being open towards said end and closed at the other end. To remove 35 the brush, the spring extension arm 27 is first raised from contact with the brush 9 by inserting the end 31 of the lever member into the housing extension 18, as indicated in dotted lines in Fig. 2, and prying 40 the spring extension arm up until the spring arm is in alinement with the lever member, at which time the lever member is pushed forward to engage the end of the spring member in the socket 30, whereby the lever member becomes a rigid extension of the 45 spring arm and the latter may be easily lifted to permit removal of the brush 9.

The rear end of the lever member is provided with a hook 32 terminating in a reduced extension 33 adapted to engage the perforation in the lug 23 on the top of the cap member 21 to facilitate the removal thereof.

While I have shown my invention in a 55 preferred form, it is obvious that many changes may be made in the details of construction and embodiment thereof without departing from the principles and spirit of my invention. I desire, therefore, that the 60 appended claims shall be accorded the broadest construction commensurate with the language thereof, when read in the light of the prior art.

I claim as my invention:

1. A brush holder for electric machines comprising an open-topped housing containing a brush box and a laterally extending spring-pressed arm for the brush, and a cap member removably closing the top of the housing. 65

2. A brush holder for holding a brush in contact with a current-collecting device of an electric machine, comprising a housing enclosed on its side, end and bottom walls and having an opening in its top wall, and a cap member removably closing said opening, said holder containing a brush box and a spiral spring mechanism for operatively supporting a brush. 70

3. A brush holder for electric machines comprising a housing containing a spring-arm mechanism for engaging the top of a brush and a brush box having its rear wall recessed to receive a portion of said spring-arm mechanism, said housing being open, at its top, behind said recess in the rear wall of the brush box, whereby said spring mechanism may be raised to provide access to said brush box, and a cap member removably closing the tops of the brush box 90 and the opening in the top of the housing. 85

4. A brush holder for electric machines comprising a housing containing a spring-arm mechanism for engaging the top of a brush, a brush box having its front and rear walls recessed to receive a portion of said spring-arm mechanism, and an open-topped housing extension enclosing a space around the recess in said front wall for receiving the end of said spring-arm mechanism, the front and side walls of said housing extension rising to the same height as the side walls of said brush box. 95

5. A brush holder for electric machines comprising a housing containing a spring-arm mechanism for engaging the top of a brush, a brush box having its front and rear walls recessed to receive a portion of said spring-arm mechanism, an open-topped housing extension enclosing a space around the recess in said front wall for receiving the end of said spring-arm mechanism, the front and side walls of said housing extension rising to the same height as the side walls of said brush box, said housing being open, at its top, behind said recess in the rear wall of the brush box, whereby said spring mechanism may be raised to provide access to said brush box, and a cap member removably closing the tops of the housing extension and brush box and the opening in the top of the housing. 100

In testimony whereof, I have hereunto subscribed my name this 11th day of June 1924.

FREDERICK W. McCLOSKEY.
